DERRICK

John Hart Wilson, Wichita Falls, Tex.

Application September 9, 1944, Serial No. 553,396

16 Claims. (Cl. 189—16)

1
This invention relates to derricks, more particularly to portable derricks composed of prefabricated units adapted for assembly on location, and constitutes a continuation-in-part of my application Serial No. 423,211, filed December 6, 1941, now abandoned.

Economical production of oil from many oil fields requires employment of derrick structures for oil well maintenance purposes. Thousands of such derricks have heretofore been and are now being used, these structures varying widely in size, general design and in detail of construction. Some are erected of wooden members, others of structural steel, and some are fabricated in part of wooden members and in part of steel members. Oil field derricks vary considerably in height but, generally speaking, most of them lie within a range of from 84 to 122 feet in height. For servicing deeper wells heights of 136 to 180 feet are sometimes required.

It is practically standard practice to construct such derricks as truncated pyramids each with four principal or corner members which are inclined upwardly and inwardly toward a common vertical axis. Because of the very considerable heights of these structures the practice hitherto has been to erect them as other buildings are constructed, i. e., by superposing part upon part and section upon section, bolting each such part in position as it is placed, beginning with the base structure and working upwardly to the crown. Erecting a derrick of any appreciable height requires a considerable expenditure of time when constructing in the manner above described. The process is costly even when prefabricated parts are used and a very considerable element of risk to the erection crew is involved.

It is the purpose of the present invention to provide a materially improved derrick structure of the prefabricated type which is of such character that it may be erected more quickly than similar structures heretofore proposed or used, which may be erected at considerably less expense than earlier types of derricks, and which is of such character and construction that the element of danger to the erection crew while assembling is greatly reduced.

The improved derrick now to be more particularly described is of a completely factory made or prefabricated type, each and every one of its parts being constructed at the plant of a fabricator. Its various parts are so designed that they may be grouped together in sub-assemblies occupying minimum space when being trans-

2
ported so that a complete derrick, capable of extension to heights beyond 100 feet, may be very conveniently transported to the location where it is to be erected. On location the sub-assemblies may be quickly positioned in proper relationship to each other and to the well platform, and final assembly quickly effected without the use of bolts. The derrick is fireproof, embodying metal parts only, and its various component elements are so designed that it may be disassembled as quickly as it may be assembled when its usefulness at any particular location is past, and transported to another location to be there erected as before and used in its new location so long as may be necessary.

In accomplishing the above described broad objectives I have evolved various new and useful structural features and relationships which cooperate to obtain the desired results in a more facile, efficient, and inexpensive manner than has heretofore been possible. Furthermore, the invention comprises a new and improved method of assembly and erection which at once greatly reduces the time required for that operation and the hazards to which the crew is subjected during the assembly and disassembly operations.

Among the important features of the invention which contribute to obtaining the above described desiderata are a simplified and effective arrangement of telescoping legs together with readily manipulable mechanism whereby inner legs may be extended individually from any of a number of operating points and with relatively little effort. In this manner the particular sequence of steps, insofar as successively erecting the various telescoped units is concerned, may be varied as to timing, etc., wherever occasion demands without in any way interfering with the broad sequence of operations.

Another important feature which contributes substantially to the simplicity of the erection operation and the rigidity thereof after erection is the improved type of girt disclosed herein and the particular manner in which it cooperates with the derrick legs to insure rigidity after positioning. The ease with which these girts may be pre-assembled and subsequently associated in the proper relationship with the derrick legs greatly facilitates the speed of erection.

An important phase of the invention resides in the manner in which the crown assembly is positioned with reference to the derrick legs after the latter have been fully extended. One aspect of this phase resides in the particular manner in which the gin poles for supporting the hoist

mechanism located at the top of the derrick are initially positioned prior to erection and the manner in which, after the leg sections have been fully extended, they are located and fixed with reference to one another with a minimum of effort and manipulation on the part of the crew. Certain adjustment features are important to this aspect of the invention.

Still another phase of the invention resides in the manner in which the crown assembly is positioned with reference to the extended legs and with reference to the gin poles aforesaid. My improved arrangement for accomplishing this, and the particular cooperative relationship of the structural parts involved permit the placement of this section with the greatest ease and a minimum of risk to the crew who, under such circumstances, are working at considerable heights.

Another feature of importance resides in the locking mechanism whereby various portions of the assembly may be quickly and securely fastened together, and whereby, when once positioned, the force of gravity functions to preclude any possible dislodgment from the relative positioning of the parts except when the locking pin is positively manipulated against such force.

As hitherto suggested, one of the most important aspects of this invention resides in the particular method or sequence of steps involved in erecting the prefabricated units whereby the same are properly assembled with reference to one another without undue difficulty and with a minimum crew utilizing no more than the power that is usually available under such circumstances for operating and servicing the well when completed.

Various other objects and meritorious features of the invention will be apparent from the following description taken in conjunction with the drawings, wherein like numerals refer to like parts throughout the several figures, and wherein:

Figure 1 illustrates one of the early stages of erection, the base leg sections and the first telescopic extension of each being in position;

Fig. 2 illustrates a further stage of erection wherein three telescopic sections of each leg are in extended position;

Fig. 3 illustrates the derrick fully assembled, although somewhat diagrammatically;

Fig. 4 is a perspective illustrating particularly the manner of positioning my improved girts and the gin pole structure at the top of the derrick;

Fig. 5 is a vertical section through one set of supporting legs in telescoped position;

Fig. 6 is a transverse section therethrough;

Fig. 7 is a vertical section through the base of the telescoped leg sections complementing Fig. 5 and illustrating the means for raising the telescoped sections successively;

Fig. 8 is a section illustrating how each leg section is held in extended position;

Fig. 9 illustrates an improved girt assembly, partially broken away and in section, positioned with reference to two adjacent leg sections;

Fig. 10 is a section through a leg section illustrating the action of a girt clamp in positioning a girt with reference to a leg section;

Fig. 11 is a side elevation of a girt clamp in locked position;

Fig. 12 is a sectional view illustrating the pin lock by which each clamp is positioned with reference to its respective supporting leg section;

Fig. 13 is a perspective of a locking pin per se;

Fig. 14 illustrates, partially in section, improved means for detachably connecting one end of a girt to a leg section;

Fig. 15 is a side elevation of the top or crown supporting leg section;

Fig. 16 is a top plan view of the structure illustrated in Fig. 15;

Fig. 17 is a vertical section therethrough;

Fig. 18 is a section through 18-18 of Fig. 15;

Fig. 19 is a top plan view of the gin pole assembly at the top of the derrick structure;

Fig. 20 is an exploded view thereof illustrating the manner of positioning the gin poles;

Fig. 21 is a perspective of the gin pole top shown at the lower left of Fig. 19;

Fig. 22 is a section through 22-22 of Fig. 19;

Fig. 23 is a top plan view of the crown block assembly;

Fig. 25 is a plan view illustrating the initial stage of assembly and erection;

Fig. 26 is a side elevation illustrating subsequent stages of erection;

Fig. 27 is a perspective illustrating a complete base assembly and its manner of erection;

Fig. 28 is an elevation of a hoisting arrangement whereby the transformation from the position illustrated in Fig. 25 to that illustrated in Fig. 27 is obtained, and

Fig. 29 is a top plan view of one of the braced gin pole and pulley sheave assemblies used for such hoisting.

When completed and ready for operation on an oil field location the derrick appears as shown somewhat diagrammatically in Fig. 3 of the drawings and may be said to comprise a rectangular base structure upon which a pyramidal superstructure rises to a considerable height. The base is broadly indicated by the numeral 10 and the pyramidal superstructure erected thereon comprises four extended telescopic supporting legs, each of which in the form illustrated consists of sections 12, 14, 16 and 18. Upon this superstructure is positioned a crown assembly broadly designated by the letter E. The base construction, the crown assembly positioned at the top of the superstructure, and the method of erection will be taken up in greater detail hereafter.

The telescoping arrangement of the four leg sections and the manner of extending them successively to the positions illustrated in Figs. 1, 2 and 3 may be most clearly described in conjunction with Figs. 5, 6 and 7, wherein the leg sections 12, 14, 16 and 18 are illustrated in collapsed position. Each telescoping section is generally tubular in cross section and, in the form illustrated, each of the sections 14, 16 and 18 are of successively reduced outside diameter with respect to base section 12 so that when the tubes are nested there is a space, crescent-shaped in cross section, between the outer surface 7 each inner tubular section and the inner surface of the next adjacent outer section forming a passage through which hoisting cables 26, 28 and 30 pass freely.

Caps 32 are slipfitted over the upper ends of sections 12, 14 and 16 and each is positioned by means of several cap screws 20 which pass through openings in the wall of the cap into drilled and tapped holes in the wall of the leg section. Each cap has welded thereto or formed integrally therewith a bracket 34 embodying bifurcated arms on which is journaled a pulley 36 over which the hoisting cable connected to the next adjacent inner leg section passes. Associated in similar manner with each cap 32 and be-

low bracket 34 there may be another bracket 22 embodying bifurcated arms between which is supported a rod 24 adapted to receive the hooked upper ends of a ladder 102.

Referring now to Fig. 7, a base plug or shoe 38 having a shoulder 40 seated against the lower end of the wall of each leg section is secured in the base of each of the leg sections except lower section 12, as by welding or otherwise. Sections 12 are hingedly secured as indicated at 188 to the assembly base, as will be described more fully in connection with Figs. 25 and 26. Each base plug 38 functions as an anchor for the hoisting cable associated with that particular leg section. The lower end of each cable passes through an opening 42 formed in the wall of each leg section near the base thereof, which opening is preferably formed by drilling a hole in the tube wall and thereafter deflecting inwardly a narrow section 44 of the wall immediately above the drilled opening. The base plug 38 is provided with a tapered passage 46 within which the hoisting cable end is retained, the terminals of the several strands being turned upwardly as indicated at 48 and embedded in babbitt or other cast metal.

It will be apparent that by manipulating the hoisting cables 26, 28 and 30 the tubular leg sections may be successively raised, thus ultimately extending the superstructure to the full height permitted by the lengths of the respective tube sections. Each section after being raised to extended position is locked in such position by means of the lock pin arrangement disclosed in Fig. 8 wherein leg section 14 has been raised to fully extended position and the base plug 38 is only about five feet below the cap 32 of leg section 12. The two sections are secured in this position by means of a pin 31 which is inserted through registering apertures in the wall of leg section 12 and in reinforcing plates 33 welded to the outer face thereof to provide additional bearing area for the shank of the securing pin 31 whereby this pin is enabled to support the weight of the leg sections above it without causing failure or bending of the wall of leg section 12. The underside of each shoulder 40 is grooved or cleft as indicated at 41 to receive pin 31 and thereby prevent rotation of each section with reference to the next adjacent lower section.

Preferably each pin embodies a weighted handle 35 and a cam section 37 cooperable with a notch 39 formed in an ambossment 43 above one of the apertures in plate 33 to retain the pin in position while handle 35 is in its normal vertically depending position.

An important phase of the invention resides in the improved arrangement for rigidifying and bracing the superstructure by means of girts, tie rods, and brace members, certain of which are of distinctly improved and novel design. The manner of assembling and positioning certain of these members with reference to the superstructure and their novel cooperative relation therewith likewise constitute important phases of the invention.

Inasmuch as the assembling and erection of the lowermost leg sections 12 into the operative position disclosed in Fig. 27 is a relatively simple operation, as will be explained in detail herein after, a simplified girt and brace arrangement is used to connect and brace the four lower sections 12. This arrangement is illustrated in Fig. 14 and consists of laterally spaced projecting flanges or ears 50 secured to the leg section and provided with aligned openings adapted to register with

an opening in the flattened end 51 of a girt 52 for reception of a locking pin 90 of the type described in detail hereinafter with reference to a different and improved form of girt. The cam 88 of the pin cooperates with a flange 94 to prevent accidental dislodgment of the pin. Ears 50 may likewise be provided with apertures to which the extremities of brace members such as those indicated at 54 may be secured.

My improved girt and the manner of its erection and assembly may be most clearly understood from Figs. 4 and 9 to 13, inclusive. Each girt consists of a central tubular member 56 to which a split clamp broadly indicated by the numeral 58 is secured. This clamp is adapted to first position the girt with reference to the legs of the superstructure as the girt is raised into position in a manner later to be described, and then lock the girt in place. With each clamp is associated one tubular girt member 56 and, at a 90-degree angle thereto, a bifurcated socket or bracket 60 adapted to receive the tongue-like extremity 62 of the next adjacent tubular girt member. Each clamp 58 comprises jaws 64 and 66 hinged to a complementary collar section 68 by means of hinge pins 70. A pin 76 is welded to the end 74 of the outer face of jaw 66 and pivotally receives the eye of an eyebolt 72, a portion of which lies within a notch 75 at the end of jaw 66 and is thereby held against displacement. The free end of jaw 64 is flared outwardly and notched or slotted as indicated at 77 to receive the threaded end of the eyebolt which, when the clamp is tightened about a leg section, is swung into the notch and then the nut 78 is tightened to force follower block 79 against the face of the flared end of jaw 64 to retain the clamp in girt-securing position. The clamp may be tightened at will by means of nut 78 threaded onto the end of the eyebolt.

To rigidify, locate and lock each girt-bearing clamp in relation to a leg section 14, such section is provided with an opening 80 with which a tubular passage 82 in lug 84, which is integral with section 68 of the clamp, is brought into alignment. On the top side of each lug 84 is an overhanging flange 86 which is adapted to cooperate with a cam section 88 on locking pin 90, which is inserted through the aligned apertures heretofore described. Each pin includes a weighted handle 92 to facilitate manipulation of the pin and serve an additional important function. On insertion, the handle 92 of the pin is held in vertical position reverse to that illustrated in Fig. 12, thus permitting cam 88 to pass the overhanging flange 86. When the pin is fully inserted the handle 92 is rotated 180° to the position illustrated in Figs. 12 and 13, thus bringing the cam 88 up under the flange lock 86, in which position it is held by gravity by virtue of the weighted handle 92. The weighted feature, furthermore, causes the pin to become locked automatically after insertion of the pin and release thereof by the workman, since gravity will then drop handle 92 to locked position.

A similar lock pin arrangement is used to connect the tongued end 62 of each tubular girt with socket 60 on the next adjacent clamp, as illustrated in Fig. 9. Each arm of socket 60 is provided with an opening adapted to register with an opening in the tongued end 62 of a next adjacent tubular girt, one of the arms being provided with an overhanging flange which cooperates with the cam section of a locking pin 90 having a weighted handle, all as described above.

In erecting the girt frame assembly described

above, the elements are laid out on the derrick floor and the tongued end of each girt is inserted between the arms of the socket on the next adjacent girt and pinned together until the four girts form a complete square frame. The jaws of the clamps 58 are then opened for all four of the derrick legs and, as shown in Fig. 4, hoisting lines or cables 96 are passed over pulleys secured to the upper ends of diagonally disposed leg sections. The free ends of the two hoisting lines 96 are split and the end of each split portion is secured to the middle of adjacent girts 56 in some suitable fashion. To avoid any tendency of the frame to warp out of its preformed square formation and thereby assume a more or less diamond shape, a rod adjustable as to length, such as a turnbuckle rod 98, may be connected to diagonally opposite corners of the assembled frame. Other means of preventing distortion of the squared frame may be utilized but the one 20 illustrated herein has been found very satisfactory.

As the girt frame is hoisted by means of the two hoist lines 96, the open jaws of the clamps at the four corners of the frame assembly function in conjunction with the leg sections as guides to position the frame with reference to the superstructure. When the frame has reached the desired position it is held there while pins 90 are inserted through the openings in the lugs on each clamp and corresponding openings in the wall of the leg section with which they have been brought into registry. The jaws 64 and 66 are then closed about the leg section and tightened in the manner aforesaid.

While ladders must be provided to permit the crew to follow the erection of the derrick, my arrangement eliminates the need for ladders on other than two diagonally opposed legs of the superstructure. In Fig. 4 I have shown ladders 100 and 102 secured by means of brackets 104 to upper leg sections 18. No ladders are required on the other legs because of my improved arrangement, assembled on the ground in conjunction with the girt frame assembly, permitting a crewman to cross from one leg of the derrick to another. This is accomplished by hanging a bar 106 consisting of a piece of pipe or angle iron from two oppositely disposed girts 56 by means of chains 108. The most convenient time for attachment is immediately after the girt frame assembly has been lifted a few feet from the derrick floor. Brace members 110 may be conveniently attached at the same time to the lower of ears 112 and 114 associated with each tubular girt 56 adjacent a clamp 58. The opening in upper ear 112 serves to anchor a brace member extending from a clamp 58 on the girt immediately above.

Bars 106 are slotted at each end as indicated at 116 and one end of a chain 118 is welded to each end of the bar adjacent the extremity thereof. The other end of each chain 118 carries an eyebolt 120. This arrangement enables a crewman operating from ladder 102 or 100 to first position the immediately adjacent clamp 58, lock the same in position with reference to its supporting leg section, and then cross over to the next adjacent leg section by means of a bar 106. When he reaches the other leg the corresponding clamp 58 is positioned and locked in place. Subsequently each chain 118 is wrapped around its adjacent leg section, the eyebolt being inserted in the slot at the end of the bar 106

and tightened to hold the bar in position as clearly illustrated in Fig. 4.

Prior to the initial stages of erection, gin poles are attached to the top leg section 18 of each telescopic assembly, each pole being seated in a socket provided at the upper extremity of said top section. Referring now more particularly to Figs. 15-18, the manner in which these gin poles are associated with the upper ends of the top leg sections and the manner of supporting the crown assembly E will be more clearly understood. Secured as by welding to the upper end of each upper leg section 18 is a member, preferably in the form of an integral casting, which includes a socket 122 adapted to receive the lower end of a gin pole 124 and a bracket 126 in which is journaled a pulley 128 for use in raising the girts, etc. Each gin pole, preferably in tubular form, has welded to it a collar 130 which includes threaded bosses 132 and 134 positioned at an angle of 90° to one another which are adapted to receive screws 136 and 138 by which the alignment of the gin poles within the sockets 122 may be adjusted. Collar 130 seats upon the wall of socket 122 and the gin pole extends well down into the socket.

As noted most clearly in Fig. 18, the inner extremities of screws 136 and 138 bear against the wall of leg section 18 and the alignment of each pole with respect to the leg section with which it is associated may be minutely adjusted for accuracy by manipulation of the screws. Ears 140 and 142 are secured to the member which includes socket 122, as by means of welding or otherwise, and are for the purpose of securing brace rods.

Over the upper end of each upper leg section 18 is seated a plate 144 which may be welded in place or otherwise secured. This plate is provided with a socket 146 tapered with respect to the axis of the leg section and adapted to receive a locating pin on one of the elements of the crown assembly and apertures 148 adapted to receive crown bolts extending from the crown block base beam, as will be more fully brought out hereinafter. On diagonally opposite leg sections 18, as with corresponding lower leg sections, ladders 100 are secured as by means of brackets 104.

In Figs. 19-22 I have illustrated the manner in which the upper extremities of the gin poles are brought together and positioned with reference to one another. The gin poles 124 are identical except for their upper extremities. At the extremity of one pole there is a top plate 150 to the underside of which is secured as by welding a cross plate 152. On each side of the cross plate 55 and at an angle of 90° thereto are secured supplemental cross plates 154 and 156, thus forming four squared sockets on the underside of plate 150. Cross plate 152 is provided with an opening 158 in which the block for raising the crown 60 may be secured.

Each of the other three gin poles is provided with a top plate 160 with an angle iron 162 welded to the lower face thereof, each angle iron 162 being adapted to slide into one of the squared sockets provided on the underside of plate 150. In the top plate 150 are three screws 166, each of which is adapted to bear respectively on a plate 160 of one of the three gin poles fitted into 70 the squared sockets beneath plate 150. Each screw 166 is preferably provided with a lock nut 164 and each screw may be adjusted to bear against the top plate 160 immediately beneath it to such an extent that each leg will support an equal portion of the load, thus distributing the

same accurately over the four gin poles and insuring rigidity of the entire crown block assembly. The gin pole with the squared sockets below plate 150 is raised first and as the other leg sections 18 are extended the plates 160-162 of the gin poles supported thereby slide automatically into the squared sockets. The adjustment of screws 166 is made after all the pole sections are in position with reference to one another. If necessary each gin pole 124 may be rotated slightly in its socket 122 to facilitate alignment in the squared sockets under plate 150 by means of the screws 136 and 138.

The crown block assembly and the manner of positioning it are most clearly illustrated in Figs. 23 and 24, from which it will be observed that the base comprises an H-shaped girder embodying end pieces 168 and 170 joined by a cross member 172. Positioned longitudinally on cross member 172 is a beam 174 to which is secured a suitable framework 176 within which a series of pulleys or sheaves 178 is journaled upon a spindle 180. A U bolt 182 is secured to the top center of framework 176. This may be utilized in conjunction with a pulley secured in opening 158 between the upper ends of gin poles 124 to hoist the crown block assembly.

Tapered pins 184 are seated in the underside of end members 168 and 170 at each extremity thereof and these are adapted to seat in sockets 146 in plates 144 supported at the upper extremity of each upper leg section 18. Thus the crown assembly may be located very quickly and simply. If necessary, leg sections 18 may be pulled inwardly or outwardly by means of suitable mechanical means, such as turnbuckles. However, it has been found that the locating pins 184 in the bottom of the crown block girder enter the sockets 146 with little maneuvering or effort on the part of the crew.

It is sometimes necessary for the crew to get up on the top of the sections 16 of the derrick and rotate by chain tongs or otherwise the top leg sections 18 since there is a tendency for the gin pole legs 124 to rotate sections 16 out of the plane necessary to bring the pole legs together properly. This may readily be overcome by standing on bar 106 and then turning the respective leg sections 18 to properly center the gin pole legs.

Openings 186 are provided at the ends of each end girder 168 and 170, these openings being so positioned that when the crown block has been located and seated upon plates 144 they register with openings 148 therein. Bolts are positioned in the aligned openings, thereby securing the crown assembly firmly to the superstructure of the derrick. In many instances it will prove advantageous to so construct the locating pins 184 that they are removable from the crown block after the same has been bolted to the superstructure.

Having described for the most part all of the articulated units of the assembly and the manner in which they cooperate with one another on complete assembly, it is now advisable to describe the new and improved method and means whereby the assembly is erected on location to obtain the finished structure illustrated somewhat diagrammatically in Fig. 3 of the drawings.

Referring now to Fig. 25, the base in the usual case will comprise three rectangular portions placed side by side to form a square. The outermost or base leg sections 12 of the telescoping tubes which form the legs are hingedly secured to the corners of the base structure as indicated at 75

188, pairs of adjacent sections 12 being hinged about axes that coincide with one another so that they may be moved upwardly in unison about said axis.

5 It should be understood that the assembly as illustrated in Fig. 25 is formed on the ground, or, if the derrick is supported on a superstructure, then suitable supports such as "horses" will be used to support the extended portion of the derrick. Girts 52 and brace members 54 are positioned as indicated before any further steps toward erection are taken. Gin poles 190 and 192 are secured to cross members 194 and 196, respectively, which cross members are in turn securely 15 fastened to the walls of the central rectangle forming a portion of the superstructure base. These gin poles are connected at their upper extremities by means of a girt 198, each end of which may be secured to one of the poles by a pin lock 200 extending through the end of the pole and the ears of bracket 202, as illustrated in detail in Fig. 29.

20 At the top of each gin pole and on opposite sides thereof are pulley assemblies 204. These assemblies are so secured to the top of each gin pole that the pulleys lie in substantially the same plane. On opposite sides of the base of the gin pole are pulleys 206 each of which is positioned on a plane normal to the plane of the two upper pulleys.

30 Ears 203 of each pulley assembly 204 are provided with openings 208 and 210. The rectangle formed by gin poles 190 and 192 and girt 198 is held in vertical position by means of brace members 212 and 214 which extend from openings 208 in the respective poles and are secured to the base frame.

35 Erection cables 222 are likewise secured in openings 210 of pulley assemblies 204 and constitute anchor points against which the tension of the erection cables operates. Erection cables 222 from their point of fixed securement to the pulley assemblies 204 pass through pulleys 224 secured to the upper portion of the respective base leg sections 12, thence around the respective pulley assemblies 204, downwardly to corresponding pulley 206, and thence to a hoisting winch not illustrated.

40 The powered ends of erection cables 222 connected to base pairs of adjacent leg sections 12 lying on the same side of the girt frame 190-192-198 are operated from the same side of the assembly. Thus one pair of erection cables 222 lying on one side of the rectangle formed by the gin pole and girt assembly functions, when hoisting power is applied by the winch, to raise a section of the superstructure lying on one side of the base frame when laid out and assembled as in Fig. 25. The other pair of erection cables 222 when powered by the hoisting winch functions to raise that section of the superstructure lying on the other side of the base frame.

45 An intermediate stage in erection is illustrated in Fig. 26 and the completion of this initial stage of erection is clearly illustrated in Fig. 27. Two girts 52 are connected up prior to the initial stage of erection, as seen in Fig. 25, and the other two girts 52 may be loosely secured, respectively, at one end to two of the leg sections 12 so that they may be easily positioned and secured after the 55 two sides have been erected to the position illustrated in Fig. 27.

50 Referring now to Fig. 25, the base in the usual case will comprise three rectangular portions placed side by side to form a square. The outermost or base leg sections 12 of the telescoping tubes which form the legs are hingedly secured to the corners of the base structure as indicated at 75

55 It has been found advisable to raise one side section at a time instead of attempting to pull them both up together. To prevent the base from lifting on the opposite side from that to which the

11

initially raised section is pivoted, both sections are placed in readiness for raising and tension is then placed on the erection lines 222 of one side section. While holding this tension with a brake, the opposite section is raised by its set of erection lines 222. When the second section is raised the weight of the section already erected is sufficient to hold down that side of the derrick base frame while the second section is being raised. This procedure eliminates the need for crewmen directing their attention to both side sections at the same time and likewise cuts down on the power required of the raising winch.

There is a tendency for the side frames or sections when raised to fall over toward the inside of the frame. To prevent this I propose to use jacks of some suitable type, such as the screw jacks 226. These jacks are used substantially as a brace rod, one for each base leg section 12. Just before each leg section reaches a vertical position the jack is attached to the leg as illustrated in Fig. 27, the base end of the jack bearing against a corner of one of the base cross beams. By operating the jack as occasion demands, each leg can be eased over to its ultimate position without the necessity of guy ropes located outside the superstructure.

When the last two girts 52 at the top of the base section of the superstructure are being secured these jacks can be used to push the leg sections 12 outwardly or allow them to fall inwardly, as may be necessary, so that the pins by which the girts are secured to the ears extending from the top of base sections 12 may be slid easily into the openings provided therefor.

As will be apparent from Figs. 25, 26 and 27, the gin poles 124 are inserted in the sockets provided therefor at the top of each innermost telescopic leg section 18 while the same are on the ground on location and before any step in the actual erection is carried out.

Having completed the sub-assembly as illustrated in Fig. 27 and positioned the same securely by means of girts 52, the leg sections 14, 16 and 18 are successively raised by means of cables 26, 28 and 30, girts of the improved type embodying clamps 58 being used at the top of each of the leg sections above base leg section 12. It is desirable also to utilize one of the improved type girts intermediate the ends of the top section 18 where the leg sections are of sufficient height to render increased rigidifying toward the top desirable. Brace rods 110 are preferably secured to the ears on the clamp members 58 prior to erection, i. e., while the structure is on the ground on location in the position illustrated in Fig. 25. The free ends of these are left dangling as illustrated in Fig. 4 as the respective leg sections are raised. After each section is fully raised and positioned the free extremities of the braces can be connected to the ears associated with the girt braces 58 of the adjacent lower girt.

When all the leg sections have been fully extended the gin poles 124 are positioned as illustrated and described in connection with Figs. 19-21, whereupon the crown block assembly illustrated in Figs. 23 and 24 is hoisted into position and locked in the manner described as aforesaid. To clear the leg sections during hoisting, the crown assembly is preferably held in offset relation to the superstructure legs during that operation and, when elevated to the necessary height above supporting plates 144, swung around into position so that locating pins 184 may be dropped into the tapered sockets 146 provided therefor.

12

After erection of all the derrick parts heretofore described, a platform for the derrick man may be hoisted into position.

The requisite procedure for disassembly or tearing down the structure is substantially the reverse of that which has been described herein.

From the foregoing it will be seen that, in addition to the legs of the derrick superstructure and the crown assembly, a number of brace rods and girts are employed to stiffen the derrick and render it truss-like in action against laterally applied forces and strong as a column when subjected to axially applied forces. The design of the several principal derrick parts whereby they may be assembled, while disposed horizontally on the ground, in such relationship to each other that the erection of the entire derrick may be effected, save only the final positioning of certain elements such as the crown assembly and platform, without successively elevating individual structural elements and bolting or riveting them into desired position as heretofore practiced, constitutes an important feature of this invention.

After use for the desired length of time at any particular station, the derrick may be dismantled almost as quickly as it has been erected, and placed upon trucks to be conveyed to some other point where it may be needed. The space required for transport is much less than that space which is required for the various parts of any other derrick of known type. The danger of erection is minimized and this is a most important feature of the invention as it is well known that there is great loss of life within and throughout the oil fields yearly due entirely to accidents occurring in the erection and dismantling of derrick structures.

Naturally, in designing the derrick structure for use in various oil fields, where requirements for 40 may vary, it may be deemed desirable to make minor changes in the design and arrangement of the component elements of the invention. Many such changes may be made without departure from the spirit and scope of the invention as it is defined in the accompanying schedule of claims.

Having thus described the invention, what is claimed as new and desired to be secured by Letter Patent is:

1. The combination of a tubular socket attached to the upper end of a top derrick leg, a gin pole having a collar adjacent its lower end, said socket receiving and supporting the lower end of the gin pole, and adjustment means carried by said collar and engaging the upper end of said derrick leg to hold the gin pole in different positions of angular adjustment with reference to its supporting socket.

2. In combination with a tubular uppermost derrick leg, a plate closing the upper end of the tube, a socket depending from said plate into the tube the axis of the socket intersecting the axis of said tube, and crown bolt receiving openings in said plate outside the confines of the tube wall.

3. A derrick gin pole assembly comprising a plurality of poles adapted for support respectively by the upper ends of derrick legs, a member secured to the upper end of one pole providing sockets adapted to receive the ends of the other poles, said member comprising a rectangular plate one quadrant of which is secured in substantially horizontal position to the end of said pole, plates secured to and depending from the

under face of said horizontal plate forming sockets beneath the other quadrants thereof, and means secured to the upper ends of the other poles forming plugs receivable in said sockets.

4. That method of erecting and bracing a derrick having a superstructure of supporting legs composed of extensible telescopic sections, a crown assembly, and a gin pole assembly at the top, which comprises the steps of positioning a gin pole for limited axial rotation on the innermost section of each leg prior to erection, successively extending corresponding sections of each leg, bracing each superstructure section as erected, rotating said poles to group and center the upper ends thereof, securing each of said poles so positioned against rotation with reference to its supporting leg section by means bearing on such section, supporting the crown assembly by said gin poles, and hoisting the same into position upon the upper ends of the upper leg sections.

5. A derrick structure comprising supporting legs each composed of a plurality of extensible telescopic leg sections, means for independently extending each section of each leg, means for securing the same in extended position, a gin pole socket and a crown-positioning socket secured to the upper end of each innermost leg section the gin pole sockets being positioned exteriorly of the crown positioning sockets, a crown assembly including depending locating pins received within the positioning sockets, and gin poles seated at their lower ends within the sockets provided therefor.

6. A derrick gin pole assembly comprising a plurality of poles rotatably supported in the upper sections, respectively, of the telescopic legs of a derrick, said poles having tapered end portions capable of meeting at an apex, a plural socket member secured to the free end of one pole, means on the free ends of the other poles adapted for reception and positioning in said sockets, and cooperating means on each gin pole and supporting leg for rotatably adjusting the relative position of the two.

7. A derrick gin pole assembly comprising a plurality of poles rotatably supported in the upper sections, respectively, of the telescopic legs of a derrick, and means carried by each pole cooperable with its supporting leg for rotatably adjusting the relative position of the two.

8. In a derrick leg the combination of a plurality of tubular telescoping leg sections of successively reduced diameter, a plug secured within the lower end of an inner section, said plug including an opening therethrough and a marginal shoulder seated against the lower end of the section, an opening in the wall of the tube section above said plug, a pulley secured to and extending outwardly from the upper end of the next adjacent outer leg section, and a hoisting cable anchored below and extending through the plug opening, the free end of said cable extending through the opening in the tube wall, between the telescoped sections and passing over said pulley.

9. The method of erecting a derrick having four legs each comprising a plurality of telescoping sections and the uppermost section of which has a gin pole mounted thereon, one such gin pole having affixed to its upper end a member provided with downwardly opening sockets for the reception of the upper ends of the other three gin poles, which comprises, extending as a preliminary operation, to the upper limit of its

travel, the upper leg section which carries the socketed member, and thereafter projecting upwardly the upper sections of the remaining legs to cause the upper ends of the gin poles carried thereby to enter the sockets of said socketed member.

10. The method of erecting a derrick having four legs each comprising a plurality of telescoping sections and the uppermost section of which has a gin pole mounted thereon, one such gin pole having affixed to its upper end a member provided with downwardly opening sockets for the reception of the upper ends of the other three gin poles, which comprises, extending as a preliminary operation, to the upper limit of its travel, the upper leg section which carries the socketed member, thereafter projecting upwardly the upper sections of the remaining legs to cause the upper ends of the gin poles carried thereby to enter the sockets of said socketed member, and finally equalizing the pressures of the gin poles last raised against said socketed member.

11. In a derrick, in combination, four legs each comprising a plurality of telescoping sections, a gin pole mounted upon the uppermost section of each leg, and a member fixed upon the upper end of one such gin pole, said member having downwardly opening sockets for the reception of the upper ends of the other gin poles whereby, after said member has been raised to final position by elevation of the leg section to which it is attached, the assembly may be completed by raising the remaining gin poles and causing the upper ends thereof to enter the sockets of said member.

12. The combination set forth in claim 11 in which said member carries adjustable means for engaging the upper ends of the three gin poles assembled therewith whereby any load applied to said member may be equally distributed to the four gin poles.

13. A gin pole construction for derricks comprising, in combination with the main derrick structure, four gin poles, a member affixed to the upper end of one such pole and having downwardly opening sockets, three additional gin poles having their upper ends disposed within three such sockets, and three adjusting elements carried by said member and engaging the upper ends of said three additional gin poles, respectively, said elements being adjustable vertically relatively to said member, whereby any load imposed upon said member can be equally transferred to said gin poles.

14. The combination set forth in claim 13 in which said means comprises three individually adjustable screws with vertically disposed axes.

15. The combination set forth in claim 13 in which said sockets open downwardly and outwardly the walls of said sockets engaging only the upwardly and inwardly facing surfaces of the respective gin poles.

16. In a derrick, in combination, four supporting legs each having a socket at its upper end, four gin poles, one associated with each leg, the lower end of each gin pole being disposed within the socket of the associated leg, each gin pole having a collar adjacent its lower end adapted to seat upon the supporting socket, lugs on opposite sides of each collar and integral therewith, each lug having a threaded opening formed therein, said threaded openings being angularly disposed with reference to each other, and adjusting screws threaded in said openings, the

15

inner ends of said screws normally engaging the associated leg, whereby each gin pole may be adjusted angularly in its socket and securely held in adjusted position.
